UNITED STATES PATENT OFFICE.

JAMES E. EASTMAN, OF PITTSFIELD, NEW HAMPSHIRE.

LANTERN-HOLDER.

1,174,700.

Specification of Letters Patent. Patented Mar. 7, 1916.

Application filed June 14, 1915. Serial No. 33,975.

To all whom it may concern:

Be it known that I, JAMES E. EASTMAN, a citizen of the United States, and a resident of Pittsfield, in the county of Merrimack 5 and State of New Hampshire, have invented a new and Improved Lantern-Holder, of which the following is a full, clear, and exact description.

My invention relates to a means for holding an ordinary lantern on a vehicle to constitute a vehicle lamp, so that a separate headlight of special construction will not need to be employed on the vehicle, and the ordinary lantern employed for the purpose 15 will be available for its ordinary uses when detached from the vehicle.

Objects of the invention are to provide a device of the indicated character comprising a lantern, a reflector, and clamp means 20 to retain the lantern and reflector firmly seated on the holder.

The invention also has for its object to provide a device of the indicated character, improved with respect to strength and efficiency, and with a view to promote convenience and simplicity in the attachment and 25 detachment of the lantern.

The invention will be particularly explained in the specific description following.

Reference is had to the accompanying drawings forming part of this specification, in which similar characters of reference indicate corresponding parts in all the views, 35 and in which:

Figure 1 is a sectional side elevation of a lantern holder and reflector embodying my invention; Fig. 2 is a front view thereof; Fig. 3 is a horizontal sectional plan view, 40 the section being taken on the line 3-3 Fig. 1; and Fig. 4 is a fragmentary side elevation of the reflector.

In constructing a practical embodiment of the invention in accordance with the form given as an example, the holder comprises a platform or seat 10, provided at the underside with a suitable clamp for securing the holder to a vehicle. The clamp as illustrated comprises a top bar 11 and depending arms 12, in one of which is provided a clamp screw 13. Preferably the connection between the seat plate 10 and the clamp 11 consists of a socket 14 on the said seat plate at the underside, a stud 15 indicated in 55 dotted lines in Figs. 1 and 2 projecting up-

wardly from the top bar 11 of the clamp, and a clamp screw 16 taking into the side of the socket 14 to bind against the said stud 15.

A reflector 17, concaved in horizontal section, is adapted to rest on the seat 10, and the base 17^a of said reflector is curved in vertical section to conform to the curved base with which the ordinary lantern indicated by the letter A in Fig. 1 is provided. 60 The base 17^a has formed thereon hook members 17^b which extend downwardly at the sides thereof at the back and terminate in forward extensions adapted to be received in holes 10^a in the seat 10. The reflector desirably will have a lens 18 preferably of red glass, the lens being held in any suitable manner as by a flange 17^c.

In order to clamp the lantern and reflector firmly on the seat 10, I provide movable clamp elements 19, these being made of wire in the instance shown and given a curvature to conform approximately to the curvature of the base 17^a of the reflector and the corresponding base of the lantern. 75 Desirably two separate clamp means are provided diametrically opposite at the back and front of the seat. Between the ends of the clamp elements 19 the same are pivoted as at 19^a on a link 20, which is made in the form of a loop, the top bar 20^a of which pivotally carries the clamp member 19, while the lower cross-bar 20^b is rockably mounted on a lever 21 having the general form of a bell crank lever and being provided with 80 a handle 21^a. The loop of each link 20 is adapted to pass over a lug 10^b formed on the seat plate 10, and the outer end of each clamp member 19 is adapted to seat on the adjacent lug 10^b as at 19^b. The lever 21 is 85 fulcrumed as at 22^a on a spring 22, which preferably is a bowed plate spring riveted or otherwise secured to the seat plate 10 as at 22^b, at about its center, leaving free resilient ends in which the levers are fulcrumed.

By the described construction a lever 21 may be swung on its fulcrum 22^a to swing a link 20 upwardly and relieve the pressure of the spring 22 on the clamp member 19, 105 so that said clamp member may be turned with the link 20 outwardly to clear the adjacent lug 10^b of the seat plate, thereby releasing the reflector 17 and the lantern base. On the other hand, when the lever is 110

thrown in the opposite direction with the clamp members 19 in position over the reflector and lantern, each link 20 may be swung on its upper cross-bar 20^a so that 5 the lower end will be carried inwardly past the fulcrum 22^a of the lever, thus placing the spring 22 under tension and subjecting the lever, link and clamp member 19 to the pressure of the spring.

10 Having thus described my invention, what I claim as new and desire to secure by Letters Patent, is:

15 1. A lantern holder comprising a seat on which a lantern may rest, a reflector having a base adapted to rest on said seat at a side of a lantern, the said base being formed to overlie a lantern base, and movable clamp means on the holder in position to detachably engage said reflector and a lantern base to 20 clamp the same on the said seat.

25 2. A lantern holder having means to secure the same in position and having a seat to receive a lantern, a reflector having a base formed to receive the base of a lantern and rest on said seat, separate clamping means on the holder distant from each other, in positions to directly clamp a lantern base, both of said clamping means being mounted to swing into clamping positions above the seat or 30 away from the clamping positions.

35 3. A lantern holder having means to secure the same in position and having a seat for the lantern, and clamps mounted on the holder beneath the seat and adapted to be swung over the seat at edge portions thereof to clamp a lantern in position thereon.

40 4. A lantern holder having means to secure the same in position and having a seat to receive a lantern, a reflector having a base adapted to receive the base of a lantern and rest on said seat, and clamps mounted on the holder beneath the seat adapted to be swung upwardly over the seat at edge portions

thereof to clamp a lantern in position, or to lowered positions away from said seat.

45

5. A lantern holder having means to secure the same in position and having a seat provided with lugs projecting at the edge of the seat, and clamps pivoted to the holder beneath the seat and adapted to swing over 50 the said lugs.

6. A lantern holder including means to secure the same in position and a seat to receive a lantern, and clamping means for a lantern said clamping means including a spring beneath the seat, a lever fulcrumed on said spring, a clamp element for holding a lantern to the seat, and means swingingly connecting the said clamping element with the said lever.

55

7. A lantern holder having means to secure the same in position and having a seat for a lantern, a reflector having a base adapted to receive a lantern base and rest on said seat, the said reflector having hook members 65 on the base thereof and the seat having holes for receiving said hooks, and clamp means movably mounted on the holder to engage or disengage the said reflector.

8. A lamp holder having a seat to receive a lantern and clamp means comprising a bowed spring on the holder beneath the seat, the said spring comprising a free arm, a bell crank lever fulcrumed on the free arm of the spring, a link rockably connected with the 75 lever distant from the fulcrum thereof, and a clamp member pivotally mounted on the link at the opposite end, and adapted to overlie the seat to engage a lantern thereon.

In testimony whereof I have subscribed 80 my name to this specification in the presence of two subscribing witnesses.

JAMES E. EASTMAN.
